UNITED STATES PATENT OFFICE.

THEODORE C. PROUTY, OF AURORA, ILLINOIS, ASSIGNOR, BY MESNE ASSIGNMENTS, TO
THE VAN SICKLEN COMPANY, A CORPORATION OF ILLINOIS.

SPEED-INDICATOR.

1,269,215.

Specification of Letters Patent. Patented June 11, 1918.

Application filed August 5, 1913. Serial No. 783,069.

To all whom it may concern:

Be it known that I, THEODORE C. PROUTY, a citizen of the United States, residing at Aurora, in the county of Kane and State of Illinois, have invented certain new and useful Improvements in Speed-Indicators, of which the following is a specification.

This invention relates to speed indicators adapted to be operated by fluid under slight or varying pressures so as to register the speed of a rotatable or any desired moving body. It relates specifically to that class of mechanism known as automobile speedometers, all of which will more fully hereinafter appear. The principal object of the invention is to provide a speed indicator of such form and construction that the least number of parts may be used in the construction thereof.

A further object of the invention is to provide a speed indicator adapted to be operated by air under slight or varying pressures and with a minimum amount of air so that it is susceptible to slight changes in the pressure and at the same time to register the same steadily, faithfully, and accurately.

The invention consists principally in the combination of a floating dial, and by that I mean, a dial that is not connected with or directly operated by positive actuating mechanisms, a base portion, and a calibrating wall, the three parts of which are arranged to form an operating chamber in connection with a movable body arranged in said operating chamber so as to operate or control the movements of the floating dial as the air or other fluid under pressure passes through the operating chamber.

The invention consists further and finally in the features, combinations and details of construction hereinafter set forth and claimed.

In the art to which this invention relates it is well known to engineers and skilled artisans of the art who have for a long time been acquainted with the objections of the present forms and constructions of the speed indicators or speedometers, as they are more properly termed, that they are made up of a large number of parts and arranged to be operated either directly mechanically or by the assistance of electro-magnetic mechanisms, all of which are intricate, making it

difficult for the ordinary individual to understand, operate or maintain. The problem presented to the art has been known for a great many years and many attempts have been made to provide a suitable speed indicating or registering device that could be operated by fluid under slight or varying pressures, but none of these mechanisms has as yet satisfied the wants or needs of the art and have not been adapted to nor adopted by the manufacturer or users of the modern automobile.

Recognizing these disadvantages, I have endeavored to simplify the construction so that my device is reduced to its absolute simplicity; is capable of being operated by a very slight amount of moving air or other gaseous fluid and will steadily and faithfully, as well as accurately, register the true speed or movements of the desired body.

I have not only had all of these objects in mind, but I have designed and constructed a mechanism which is so simple that the ordinary artisan or even the user of an automobile can take the mechanism apart for the purposes of renewal or adjustment, as occasion may require, and put the same together without experiencing any difficulty whatever, all of which will fully appear in the accompanying description and drawings which form a part of this specification.

In the accompanying drawings—
Figure 1 is a front view of a speedometer or speed indicator constructed in accordance with these improvements and showing the speed indicating device at the upper portion thereof and in vertical cross section, the lower portion showing the mileage register which forms no part of this invention and which is merely inserted for the purpose of illustrating to the art how my invention may be combined or arranged in connection with a mileage register.

Fig. 2 is a plan view looking at the device from above and showing a portion thereof in cross section.

Fig. 2^a is a plan view showing the attachment of the hair spring to the cup-carrying staff.

Fig. 3 is a perspective view of a floating dial with its attached mechanisms, looking at it from below.

Fig. 4 is a perspective view of the sup-

porting base with its calibrating wall and attached mechanisms looking at it from above.

Fig. 5 is a front elevation of a complete instrument made in accordance with my improvements and suggestions.

Fig. 6 is a side elevation thereof showing the floating dial in dotted outline and the instrument connected by means of a tube with a suitable air pump or agitator; and

Fig. 7 is a cross sectional detail of a portion of the mechanism taken on the curved line 7—7 of Fig. 2, looking in the direction of the arrows.

In constructing a speed indicator in accordance with my improvements I provide what I prefer to term a floating dial having a cylindrical body portion 1 bearing the necessary indicating characters *a* on the external surface thereof, which characters are shown particularly in the upper portion of Fig. 5. This floating dial is preferably made of a very light material such as aluminum, and is provided with a head or cap portion 1^a, as shown particularly in Fig. 1, which in connection with the cylindrical body portion, assists in forming a portion of an inclosing casing for the operating chamber 2.

I term this dial portion a floating dial in that it practically floats, oscillates, or rotates free from all other mechanism, that is, it is not operated by gears or electromagnetic machinery of any kind, but floats, oscillates, vibrates, or rotates simply and solely by the action of air or a gaseous fluid under movement, all of which will more fully hereinafter appear.

In order to complete the operating chamber, I provide a base portion 3 having a cylindrical calibrating wall portion 4, the upper edge of which, or what I prefer to term its calibrating edge 5, is substantially helically arranged, as shown in Figs. 1 and 4, this helical arrangement being that necessary in the embodiment shown.

It will be seen that this base portion, cylindrical wall and the floating dial inclose the space 2 which I have termed the operating chamber and that the calibrating edge of the circular wall of the base portion is helically arranged so as to present a space above the same and underneath the cap of the dial of varying area, that is, presents an increasing or decreasing sectional area, as you look at and understand the operations of the completed device. This base portion is further provided with a centrally located hub portion 6, and what I prefer to term a fixed abutment 7 extending from the central hub to the calibrating wall and which separates the inlet opening *b* from the exit opening *c*, that is, the air or other gaseous fluid under pressure may enter the operating chamber through the inlet opening *b*,

but it has to go around the centrally located hub and make a complete circuit of the operating chamber before it reaches the exit chamber *c*, the purpose of which will more fully hereinafter appear as I describe more in detail the other mechanisms and their operations.

To support the floating dial in a balanced way, I use what I prefer to term a balance-staff 8 and secure it to the cap of the floating dial between flanges or in any other desired manner. This balance-staff is constructed very much like the balance-staff of a watch or clock and is as usual provided with pivotal points, the lower one of which is mounted in any desired jewel, either metal or stone 9, at the bottom of the centrally located hub, and the other or upper point in a pivotal bearing in the upper part of the cross bar 10 of the supporting frame. This cross bar or bridge, as shown particularly in Fig. 2, is substantially of inverted U-shape, one leg of which is attached at its bottom portion by means of small machine screws 11 to the lower frame portion 10^a, and is passed over and across the device and down with the other leg fastened by means of similar screws 11 to the diametrically opposite portion of the frame.

To operate or move the floating dial by air or other gaseous fluid, as it passes through the operating chamber of the instrument, a vane portion 12 is provided and preferably in this instance is secured directly to the dial itself, that is, to the cap portion thereof and should also be made of very light material such as aluminum. This vane, as shown particularly in Fig. 1, substantially fits one radial sectional part of the operating chamber with the exception that there is a small passage therebetween and the portions of the supporting base around which a certain amount of the air or fluid may pass. It will be further seen that directly at the left-hand end, the vane presents or forms in connection with the cylindrical calibrating wall and the inner cylindrical surface of the floating dial a by-pass 13.

It will be further seen that as this vane is moved one way or the other from the position shown in Fig. 1 it presents to the air or gaseous fluid a by-pass of varying size, that is, of increasing or decreasing area. In short, the vane constitutes a species of valve member movable with respect to and coacting with the outlet by-pass. This arrangement is such also that as the body of air or gaseous fluid increases in speed or volume it moves the vane around in such a manner as to present a by-pass of gradually increasing or cross sectional area; but when the speed of the moving body of gaseous or other fluid decreases the vane is moved back by means hereinafter described and presents or uncovers a by-pass in a varying or de-

creasing cross sectional area, so that a lesser amount of fluid may pass around through the by-pass.

- To yieldingly hold the dial with its vane in desired operating position, as well as to return it to its normal or zero position, a hair spring 14 is provided, the outer end of which is attached at 16^a to an adjustable arm 15 mounted on the supporting cross-bar 10, while the inner end is preferably attached to a collet or collar 16 mounted on the upper end of the balance-staff, all of which is so arranged that any desired tension may be placed upon the hair spring by moving the adjustable arm in one direction or the other, thus regulating the sensitiveness of the dial with its attached vane.

The operating chamber, or the inlet opening thereof, may be connected with a desired air pump or agitator 17 by means of a flexible tube 18. This air pump or agitator may be so arranged as to be operated directly by the rotation of any rotatable or moving part of the automobile or other device, the movements of which it is desired to indicate in any manner thought desirable by the user.

It will be understood by those skilled in the art after a careful reading of the foregoing specification and an examination of the drawings, that the device is susceptible to the very slightest movement of gaseous fluid, particularly atmospheric air, and that the passage of the same therethrough may be controlled in any desired manner, that is, the calibrating edge 5 of the circular wall 4 may be cut away in any desired manner so as to obtain a variety of registrations, and further in the case of error on test it may be cut away to correct irregularities or errors in a very easy and simple manner.

I have shown this instrument, as already stated, in Figs. 1, 2, 5 and 6 in connection with the complete instrument in which there is a mileage register, the numerals 19 and 20 indicating season and trip mileage, all put in one inclosing casing 21, but this mileage register does not form, as I have already stated, any part or portion of this invention. It is merely shown herein to teach those skilled in the art how the two devices may be assembled in one complete organized instrument.

In operation the device is set in any desired position and connected with an air pump or any other fluid agitator by means of one or two tubes, as may be desired, one of which should preferably be connected with the inlet opening *b* of the operating chamber. During the operations of the machine, which in turn operates the agitator, air is furnished the operating chamber and is compelled by the fixed abutment to pass therearound or therethrough, coming in contact with the movable vane. The passing of

the air under slight or varying pressures moves the vane to the desired position so that the surplus will pass around the vane and through the by-pass, meeting the other quantity of air and emerging through the exit opening. The hair spring presents a yielding resistance to the movement of the dial beyond a certain predetermined point, according to the amount of fluid that is passing through the operating chamber, and the user in looking at the instrument, as shown in Fig. 4, sees the figure as presented through the sight opening in the external casing and thereby is informed of the speed at which the body is moving. A reduction in the speed reduces the quantity of air supplied to the operating chamber and the hair spring compels the dial to begin a retrograde movement and show a reduced figure on the dial. Any increase in speed supplies a greater quantity of air which impinging against the movable vane forces it around against the yielding resistance of the hair spring so as to present a higher number on the periphery of the dial, all of which those skilled in the art will fully understand.

I claim:

1. In a fluid actuated speed indicator or similar instrument, the combination of a casing providing an operating chamber and having an inlet and an outlet in connection therewith, said outlet being calibrated to afford exact indication of different speeds, an actuatable member pivotally mounted and arranged to be operated by the fluid as it passes through the operating chamber, indicating means coacting with said actuatable member, and means for yieldingly holding said actuatable member and its indicating device in operative position, said means operating to return it to its normal or zero position.

2. In a fluid actuated speed indicator or similar instrument, the combination of a casing providing an operating chamber having inlet and outlet openings and a by-pass varying in cross sectional area, a vane pivotally mounted in said casing and transversely of said operating chamber so as to oscillate therein and coact with said by-pass to utilize cross sectional areas thereof varying for different speeds, indicating means associated with said vane, and a spring for yieldingly holding said vane with said indicating means in position and operating to return it to its normal or zero position when not in operation.

3. In a fluid actuated speed indicator or similar instrument, the combination of a casing providing an operating chamber having inlet and outlet openings and provided with a by-pass of varying cross sectional area, a staff pivotally mounted in said casing and carrying an indicating device and also provided with a vane secured thereto

and oscillatingly movably held in the operating chamber, so as to coact with said by-pass to present a cross sectional area thereof varying for different speeds, and retarding devices for said indicating staff.

4. In a fluid actuated speed indicator or similar instrument, the combination of a casing providing an operating chamber having inlet and outlet openings and provided with a by-pass of varying cross sectional area, a staff pivotally mounted in said casing and carrying an indicating device and also provided with a vane secured thereto and oscillatingly movably held in the operating chamber so as to uncover and cover said by-pass to present a cross sectional area thereof varying for different speeds, and a spirally coiled hair spring having one end secured to said indicating staff and the other end to a non-movable portion of said device.

5. In a fluid actuated speed indicator or similar instrument, the combination of a casing providing a substantially circular operating chamber and a by-pass of varying cross sectional area and an abutting separating wall transversely arranged in said operating chamber and forming the end wall of said chamber when the device is in assembled position, said indicator being provided with inlet and outlet openings communicating with said chamber, one arranged on each side of said abutting separating wall, a staff pivotally mounted in said casing and carrying an indicating means and a vane, said vane being oscillatingly movably held in said operating chamber between the inlet and outlet openings thereof so as to uncover or cover the said by-pass and present cross sectional areas thereof varying for different speeds, and a hair spring secured at one end to said operating staff and having its other end fixed so as to yieldingly hold said indicating staff against movement and serving to return the same to normal or rest position.

6. In a speedometer, the combination of a pump, a fluid actuated speed indicator having a fluid conducting chamber receiving fluid from said pump, pivoted valve mechanism operatively associated with said fluid conducting chamber and arranged to be actuated by the fluid pumped through said chamber, and means presenting an increasing resistance to said valve as it moves in one direction, said chamber having a port, the effective area of which in cross

section varies with the position of said pivoted valve.

7. In a speed indicating device, a supporting framework, a floating dial having indicating characters thereon, a balance staff carrying said dial and pivotally mounted, a member forming with said dial a casing having an operating chamber with an inlet opening through which fluid is passed, said operating chamber being provided with a calibrating member having a calibrating edge portion forming in conjunction with said casing a by-pass of varying cross sectional area, a vane movably mounted in said operating chamber for operating said floating dial and arranged to be operated by the fluid passing through the chamber so as to coact with the calibrating edge portion of said calibrating member to present a by-pass of cross sectional area varying for different positions of said vane.

8. In a device of the class described, a fixed member and a movable dial, said member and dial forming an operating chamber, a sleeve projecting from said fixed member, a bridge, a staff carried by said dial and having one end pivotally mounted in said bridge, the other end being pivotally mounted in said sleeve.

9. In an instrument of the class described, the combination of a rotatable indicating dial having a peripheral wall, a fixed member, said fixed member and dial forming a chamber, a vane associated with said dial, said chamber being provided with an inlet and an outlet, a wall carried by said fixed member and located adjacent said peripheral wall of said dial when in assembled relation, said wall being provided with a calibrating edge portion arranged to coact with said dial wall and said vane to provide a by-pass of cross sectional area variable for varying positions of said vane whereby fluid supplied to said chamber will actuate said vane in accord with the speed of the device whose speed is to be indicated, said variable by-pass being operative to determine the movement from rest or zero position of said dial in the desired ratio to the speed of the device whose speed is to be recorded.

In testimony whereof I have subscribed my name.

THEODORE C. PROUTY.
